CLAIM

The ornamental design for a set of cuffs for a garment as shown and described.

DESCRIPTION

FIG. 1 is a front view of the cuff design, provided on right and left sleeves of an exemplary jacket, wherein the right and left cuffs are mirror images of each other and are in unfastened condition.

FIG. 2 is a back view of the cuff design of FIG. 1.

FIG. 3 is a back-right perspective view of the right cuff of FIG. 1.

FIG. 4 is a front-right perspective view of the right cuff of FIG. 1.

FIG. 5 is a close-up detail of FIG. 3.

FIG. 6 is a close-up detail of FIG. 4.

FIG. 7 is a front view of the right cuff of FIG. 1.

FIG. 8 is a bottom view of the right cuff of FIG. 1.

FIG. 9 is a back view of the right cuff of FIG. 1.

FIG. 10 is a top view of the right cuff of FIG. 1.

FIG. 11 is a left end view of the right cuff of FIG. 1; and, FIG. 12 is a right end view of the right cuff of FIG. 1.

The even broken lines showing the garment illustrate environment of the set of cuffs that form no part of the claimed design. The dot-dot-dash broken lines included in the drawings show the bounds of the claim and form no part of the claimed design.

1 Claim, 11 Drawing Sheets
